CLAIM

The ornamental design for the arm locking mechanism for side out awning, as shown and described.

DESCRIPTION

FIG. 1 is a fragmentary view of the arm locking mechanism for side out awning showing the environment in which the invention is used;

FIG. 2 is a perspective view of the arm locking mechanism for side out awning illustrated in FIG. 2;

FIG. 3 is a front view of the arm locking mechanism for side out awning illustrated in FIG. 2;

FIG. 4 is a side view of the arm locking mechanism for side out awning illustrated in FIG. 2;

FIG. 5 is a rear view of the arm locking mechanism for side out awning illustrated in FIG. 2;

FIG. 6 is an opposite side view of the arm locking mechanism for side out awning illustrated in FIG. 4;

FIG. 7 is a top view of the arm locking mechanism for side out awning illustrated in FIG. 2; and,

FIG. 8 is a bottom view of the arm locking mechanism for side out awning illustrated in FIG. 2.

The broken lines are shown for illustrative purposes only and form no part of the claimed design.
